214,913

HOLDER FOR TELEVISION ANTENNA

Robert G. Shorr, 46 Venetian Way,
Miami Beach, Fla. 33139

Filed Dec. 2, 1968, Ser. No. 14,745

Term of patent 14 years

Int. Cl. D14—99

U.S. Cl. D26—14

Fig. 1

Fig. 2

The broken lines are shown for illustrative purposes only.

I claim:

The ornamental design for a holder for television antenna, as shown and described.
